U.S. Appl. No. 29/465,542, filed Aug. 29, 2013, Judson et al.

Primary Examiner — Barbara Fox*Assistant Examiner* — Lilyana Bekic(74) *Attorney, Agent, or Firm* — Nixon & Vanderhye P.C.**CLAIM**

The ornamental design for a respiratory mask cushion, as shown and described.

DESCRIPTION

FIG. 1 is a front perspective view showing a respiratory mask cushion according to a first embodiment of our new design; FIG. 2 is a reverse perspective view thereof; FIG. 3 is a front view thereof; FIG. 4 is a rear view thereof; FIG. 5 is a top view thereof; FIG. 6 is a bottom view thereof; FIG. 7 is a left side view thereof; FIG. 8 is a right side view thereof; FIG. 9 is a front perspective view showing a respiratory mask cushion according to a second embodiment of our new design; FIG. 10 is a reverse perspective view thereof; FIG. 11 is a front view thereof; FIG. 12 is a rear view thereof; FIG. 13 is a top view thereof; FIG. 14 is a bottom view thereof; FIG. 15 is a left side view thereof; and, FIG. 16 is a right side view thereof.

The broken lines in the drawings illustrate portions of the respiratory mask cushion that form no part of the claimed design.

1 Claim, 8 Drawing Sheets**Related U.S. Application Data**

continuation of application No. 29/311,161, filed on Jan. 6, 2009, now Pat. No. Des. 614,290, which is a division of application No. 29/258,084, filed on Apr. 14, 2006, now Pat. No. Des. 587,800.
